UNITED STATES PATENT OFFICE.

ELLSWORTH W. S. DAAB, OF NEW YORK, N. Y.

LEVEL.

1,202,167.

Specification of Letters Patent.

Patented Oct. 24, 1916.

Application filed May 4, 1915. Serial No. 25,802.

To all whom it may concern:

Be it known that I, ELLSWORTH W. S. DAAB, citizen of the United States, residing at New York, in the county of New York and State of New York, have invented certain new and useful Improvements in Levels, of which the following is a specification.

My invention relates to levels and more particularly to an attachment therefor.

The object of the invention is to provide an improved level device or measure whereby two "determining" quantities may be ascertained through use of the device as a level and subsequently, through simple multiplication, the "determined" quantity quickly ascertained without a re-use or second application of the device.

The invention consists in the construction and combination of parts to be more fully described hereinafter and particularly set forth in the claims.

In the drawings: Figure 1 is a view of my improved level in side elevation; Fig. 2 is a top plan view; Fig. 3 is an end view; Fig. 4 is a longitudinal sectional view, partly broken away; and Fig. 5 is a similar view, the section being taken transversely to that of Fig. 4.

Like numerals of reference designate like or corresponding parts throughout the several views.

Coming now to a description of the drawings by numerals, 1 designates a stock equipped with horizontal and plumb spirit levels of an accepted design, the spirit levels being designated respectively 2 and 3 and inlaid in a manner old in the art. The stock 1 is cut away at one end as indicated at 4 to receive a knob 5 and protector plate 6 therefore, the latter, plate 6, being affixed as at 7 to the stock 1 in such relation to the mentioned knob as to receive the wear and tear incident to manipulation of the latter as will hereinafter appear.

A transverse or vertical recess 8 is formed in the stock 1 to receive therein a vertically movable rod or rack bar structure 9. Teeth 10 are formed on the inner longitudinal edge of the rod 9 to mesh with the teeth of a worm gear 11, the latter being affixed in any suitable manner to an operating rod 12 turnable through manipulation of the mentioned knob 5. Recess 8 does not extend entirely across the stock 1, but terminates in such adjacency to the knob 5 as to

afford a bearing surface 13 for the operating rod 12. The opposite end of the mentioned rod is journaled as indicated at 14 in a plate 15 affixed as at 16 to the under side or edge 60 of the level stock, the said plate also affording a closure at the base terminal of the recess 8.

Longitudinal flanges 17 are formed upon and at opposite sides of the rod 9 to operate 65 within complementary grooves 18 therefor formed in the stock 1 of the level, the engagement of the parts thus mentioned precluding casual displacement of the rod and directing its movement during adjustment 70 through manipulation of the knob.

Graduation marks 19 are arranged preferably at opposite sides of the recess and upon metallic protector plate 20, the marks thus provided indicating to the user the 75 movement, in inches, of the rod 9. As shown to advantage in Fig. 3 rod 9 has been moved seven sixteenths of an inch, each inch being subdivided into a sixteenth part.

The periphery of the knob 5 is graduated 80 as indicated at 21, the graduation marks dividing the circumference of the knob into sixteen equal parts. The graduation marks are adapted for registry with a mark 22 formed on the plate 20 directly beneath the 85 knob. The teeth on the worm gear structure 11 are of a suitable pitch whereby to move the rod 9 one-sixteenth of an inch incident to a complete revolution of the knob. By such an arrangement, and by so graduating the knob and the mentioned plate, it is apparent that the rod 9 may be accurately adjusted to a two-hundred and fifty-sixth of an inch. 90

In use, the length of the level will afford 95 one of the known quantities, the distance between the top end of the rod 9, and the top of the recess 8, the other of the known quantities, while the unknown quantity to be determined is ascertained by multiplication. 100

In reduction to practice, I have found that the form of my invention, illustrated in the drawings and referred to in the above description, as the preferred embodiment, is 105 the most efficient and practical; yet realizing that the conditions concurrent with the adoption of my device will necessarily vary, I desire to emphasize the fact that various minor changes in details of construction, 110 proportion and arrangement of parts may be resorted to, when required, without sac-

rificing any of the advantages of my invention, as defined in the appended claims.

Having thus fully described my invention, what I claim as new and desire to secure by Letters Patent, is:—

1. The combination with a level, of a slide member mounted at one end thereof and in proximity to graduation marks formed on said level to indicate relative movement of said slide and level, and a graduated means turnable to move said slide and indicate to a greater degree of minuteness, the relative movement of said slide.
2. The combination with a level, of a measuring device mounted for sliding movement within a recess therefor formed in the level at one end thereof, the level being provided with graduation marks at one side of said recess, means turnable to slide the measuring device, said means being provided with graduation marks upon its periphery to ascertain with accuracy the degree of movement of the measuring device.
3. The combination with a level, of a slide device mounted in a recess therefor at one end of the level, the level being graduated at one side of the recess, means turnable to

slide the device, one complete revolution of said means moving said device the distance between adjacent graduations at the side 30 thereof, said means being in turn graduated to indicate the degree of movement of said device intermediate the marks first mentioned.

4. The combination with a level, of a slide 35 member located in a recess therefor formed in the level at one end thereof, said recess having lateral recesses, projections on the slide for engaging the lateral recesses, and turnable means mounted to engage said slide 40 member to move the same one complete revolution of said means moving said slide a predetermined distance indicated by graduation marks at the end of the level, said means being in turn graduated to indicate 45 to a greater degree of minuteness the movement of the slide when it is desired accurate adjustment be afforded.

In testimony whereof I affix my signature in presence of two witnesses.

ELLSWORTH W. S. DAAB.
